UNITED STATES PATENT OFFICE.

HENRY S. HORNBECK, OF ELIZABETH, NEW JERSEY, ASSIGNOR TO VOLOTONE COMPANY, OF ELIZABETH, NEW JERSEY, A CORPORATION OF NEW JERSEY.

MUSICAL INSTRUMENT.

1,142,255.

Specification of Letters Patent.

Patented June 8, 1915.

Application filed August 11, 1909. Serial No. 512,465.

To all whom it may concern:

Be it known that I, HENRY S. HORNBECK, a citizen of the United States, residing in Elizabeth, in the State of New Jersey, have 5 invented certain new and useful Improvements in Musical Instruments, of which the following is a specification, reference being had to the accompanying drawings, forming a part hereof.

10 The purpose of this invention is primarily and generally the improvement of mechanical piano-playing devices, although, as will more clearly appear hereinafter, the invention is applicable, in part at least, to 15 ordinary pianos and similar instruments.

One object is improvement in the character of the touch or the quality of the blow with which each tone is produced, and especially the substantial elimination of the mechanical quality of the touch which, in greater or less degree, has hitherto characterized mechanical playing devices, and the 20 production of a touch more closely resembling than heretofore has been possible the 25 touch of the skilled human fingers.

Another object is to make possible any gradation of force, with which tones are produced, and therefore of strength of tone produced, either of single tones anywhere 30 in the range of the piano or of a group of tones, and especially to achieve, in mechanical playing devices, the possibility of both rhythmic and sub-accent which has hitherto 35 been practically beyond the power of mechanical playing devices.

Still another object is to make possible the performance of musical compositions by mechanical playing devices in a manner comparable to performances by skilled artists, 40 and especially to make it possible to let the melody of the composition predominate throughout the composition with any degree of expression both in the melody itself and in the subordinated harmony.

45 Other objects, more or less incidental to these main objects, will appear hereinafter.

These various objects are attained in part by supporting or suspending movably or 50 yieldingly the fulcrum of each transmitting lever or finger (as the part referred to is commonly termed in mechanical playing devices) or key (as the part is termed in an ordinary piano) or other part of the playing mechanism through which the impulse is 55 transmitted from the actuator to the ham-

mer, either indirectly through the piano key, as in mechanical playing devices outside of the piano case, or directly as in an ordinary piano. Preferably each fulcrum is spring suspended and provisions are made whereby 60 the degree of elasticity in the spring may be varied at the will of the performer. The objects are also attained in part by certain novel combinations of elements which may or may not include such yieldingly suspended fingers.

The invention will be more fully explained hereinafter with reference to the accompanying drawings in which it is illustrated and in which—

Figure 1 is a view in front elevation of an ordinary cabinet player to which the invention has been applied, parts with which the invention is not concerned being shown merely in outline or not shown at all. Fig. 2 is a view partly in end elevation, as seen from the left hand in Fig. 1, and partly in section, showing only parts which are involved in the invention, the piano and its key-board being indicated by dotted lines. Fig. 3 is a detail plan view, on a larger scale, of the controller. Fig. 4 is a view in side elevation of the controller. Fig. 5 is a detail view of one of the valves shown in Figs. 3 and 4. Fig. 6 is a detail view in rear elevation showing two of the fingers and their supporting and controlling devices. Fig. 7 is a view of the parts shown in Fig. 6 as seen from the right hand in Fig. 6, partly in elevation and partly in section. Fig. 8 is a detail view in front elevation of the parts shown in Fig. 6, except that the connection of the crescendo devices to the hand controlling device is indicated in Fig. 8 while in Fig. 6 the connection of such devices to the pneumatic controlling device is indicated. Fig. 9 is a partial view similar to Fig. 7 but showing the parts in different positions. Figs. 10 and 11 are detail views in rear and side elevation, with parts in section in Fig. 11, illustrating an application of the invention to a player-piano. Fig. 12 is a detail view of the fulcrum spring shown in Fig. 11. Fig. 13 is a view illustrating an embodiment of the invention in an electrically actuated player. Fig. 14 is a detail view of the controller shown in Fig. 13. Figs. 15 and 16 are diagrammatic views illustrating the electrical connections in such a player as that indicated in Fig. 13.

110

When the invention is applied to an ordinary cabinet piano-player, that is, to playing devices which are outside of the case of a piano and in which the fingers of the playing devices act directly upon the keys of the piano, no modification of the ordinary playing devices is required, the invention being capable of being embodied in an attachment which may be applied to any ordinary cabinet player. Furthermore, the devices with which the invention is concerned are independent of the ordinary playing devices, which may be of any usual or suitable character. It is, therefore, unnecessary to illustrate or explain in detail the ordinary playing devices and they are not shown herein so far as concerns the embodiment of the invention in such a cabinet player, except as to the fingers, which replace the fingers ordinarily employed, and the connections thereof to their actuating bellows.

In the embodiment of the invention in the cabinet player which is chosen for illustration in Figs. 1-9, the cabinet *a* is shown as supporting the usual tracker board *a'*, feed roll *a²* and below or at the right hand of the tracker mechanism, the usual devices *a³* for regulating the tempo and expression. At the left hand of the tracker board, in convenient position for operation by the left hand of the performer, is mounted the controller by which, in a cabinet player such as is represented, the operations of the devices with which the invention is particularly concerned are controlled or regulated. This controller, in the form chosen for illustration, is shown in position in Figs. 1 and 2 and is shown more in detail in Figs. 3 and 4. As there represented, it comprises a board *b*, preferably quadrant shaped, which is supported at its outer end upon a spring *b'* and is hinged at its rear end, as at *b²*, so as to swing upon a horizontal axis. An arm *b³*, extended rearwardly from the board, is connected by a link *b⁴* with one arm of a lever *b⁵*, the other arm of which is connected by a link *b⁶* through a yoke *b⁷*, with one arm of a bell-crank lever *b⁸*. The other arm of the bell-crank lever is connected with a crescendo-bar *b⁹* suitably supported by links, one of which is shown at *b¹⁰*, and held normally in its highest position by springs, one of which is shown at *b¹¹*. The relation of the crescendo-bar *b⁹* to the devices, the action of which is regulated by it, will be described later.

In the board *b*, near its forward edge, are holes *c* which form the terminals of tubes *c'* which are severally connected to several bellows *c²*, two of which are shown in Figs. 6 and 7. Each of such bellows controls or regulates, in the manner hereinafter described, the action of a small number of the key-fingers to be referred to. That any one or more of these bellows *c²* may be collapsed

and so perform the intended function at the will of the performer, it is necessary that such bellows should be capable of being placed in communication, at the will of the performer, with the vacuum system of the player.

The result last referred to is accomplished by the following instrumentalities. On the board *b* is mounted, so as to move in a plane parallel with the board *b*, a shifting connector through which connection may be established between the vacuum system of the player and any one or several of the ports *c*, tubes *c'* and bellows *c²*. In the construction shown, this shifting connector comprises a tube *c³* which is pivotally mounted in a yoke *c⁴* on the upper end of a vertical rock-shaft *c⁵*. The tube *c³* is connected by a flexible tube *c⁶* with the vacuum system, which may be arranged as usual, through a pneumatic *c⁷* which may be controlled by the performer as hereinafter described. A tube *c⁸*, arranged to telescope in the tube *c³*, carries at its outer end a head *c⁹* which is arranged to slide upon the surface of the board *b* in close contact therewith, the head *c⁹* being suitably formed so that it may be conveniently moved by the performer. In the underside of the head, as indicated by dotted lines, is an L-shaped slot *c¹⁰* which is in communication with the vacuum system through the tubes *c⁸*, *c³* and *c⁶*. The short arm of this slot, substantially parallel with the axis of the tube *c⁸*, is wide enough to cover only one of the ports *c* at a time, when the head and tube *c⁸* are pushed in, as shown in Fig. 3. The long arm of the slot *c¹⁰* is long enough to cover two or more of the ports *c* when the head is pulled out to permit this. Thus, according to the pushing in or pulling out of the head *c⁹* one or more than one of the bellows *c²* may be collapsed through the connection with the vacuum system, and according to the movement of the head to one side or the other, the bellows or several bellows which is or are thus to be collapsed, may be selected from the whole series of bellows *c²*, the whole series of key-fingers being thus placed under the control of the performer. Adjacent to the head *c⁹* is located the terminal of a tube *c¹¹* through which atmospheric pressure may be admitted to the valve *c¹²* by which the pneumatic *c⁷* is controlled. This terminal might be directly controlled by the finger of the performer, but in the construction shown in Figs. 3, 4 and 5 of the drawings, it is indirectly controlled by the finger of the operator through a valve *c¹³* which is normally held by a spring *c¹⁴* in position to close the terminal of the tube *c¹¹*. To the valve *c¹²* is connected a flexible strap *c¹⁵* connected to a fixed point on the tube *c³*, so that by pressure of the performer's finger on the strap *c¹⁵* the valve *c¹²* may be opened.

In order that the hand of the performer

in swinging the head c^6 to one side or the other and therefore in establishing connections between one or another of the bellows c^2 and the vacuum system, may follow accurately the arrangement of those perforations of the music-sheet which determine the selection of the melody tones, the shaft c^6 is connected through an arm c^{16} at its lower end and a link c^{17} with a lever c^{15} . The upper end of the latter is connected by a link c^{18} with a rod c^{20} which carries an indicator c^{21} in proximity to the tracker board. The lower end of the indicator is preferably forked, with a plurality of fingers c^{22} , the space between two of the fingers at one side of the indicator corresponding to the short arm of the L-shaped slot c^{12} , while the space between the two outside fingers corresponds to the long arm of the L-shaped slot. Therefore when the head c^6 is pushed in so that the short arm of the slot alone registers with the ports c , only the tones represented by those notes of the music-sheet which fall between the two left hand points or fingers of the indicator will be under the control of the swinging movement, while if the head c^6 is pulled out so that the long arm of the slot alone registers with the port c , all the tones represented by the notes which are embraced between two outside points or fingers of the indicator will be under the control of the left hand of the performer. Also carried with the shifting connector is the terminal of a tube c^{23} , which may be controlled either directly by the finger of the performer or by a valve c^{24} which is constructed and operated in the same manner as the valve c^{13} , already described. The tube c^{23} is connected to a pneumatic c^{25} which, in the usual manner, controls a bellows c^{26} . The movable member of this bellows is connected by a rod c^{27} (see Figs. 2, 6 and 7) with the yoke b^7 through which the crescendo-bar b^8 is operated as already described. In this manner the crescendo-bar may be operated either by hand or pneumatically. The hand operated devices, that is the devices actuated by the depression of the board b , will generally be employed when a gradual crescendo is desired, while if a crash is desired the pneumatically controlled devices, which act more quickly than the hand, will be employed.

The description thus far has been concerned mainly with the devices which are manipulated by the performer, and the connection of such parts. Consideration will now be given to the mounting of the key-fingers or levers through which the impulses are transmitted, either directly or indirectly from the actuators to the hammers or tone-producing devices and the devices which directly regulate the force of the blow which is transmitted through the key-fingers to the hammer devices. For convenience the

hammer devices and the parts which are directly connected or coöperate directly therewith and through or upon which act the devices which vary the tone and through or upon which act the player pneumatics, may be called tone producing devices. These devices are shown more particularly in Figs. 2, 6, 7, 8 and 9. Each key-finger d may be actuated by any suitable means, mechanical, electrical, pneumatic or otherwise. In the embodiment of the invention now under consideration each finger is shown as actuated through a rod d^3 from a bellows d^2 . However the key-finger is actuated, it is movable, being preferably mounted on a yielding or spring-suspended fulcrum. Any suitable form of spring suspension for the fulcrum might be employed, but to enable the advantages of such suspension to be realized most fully, each fulcrum block, or as it is commonly termed in mechanical players, the flange d^3 , in which the key-finger is pivoted, is secured to a separate flat spring d^4 , all of the springs d^4 bearing upon a common fulcrum bar d^5 and each being provided with an adjusting spring and screw, as at d^6 . A stop or rest-bar d^7 limits the downward movement of the free ends of the springs d^4 . The free end of each spring is also preferably stepped or bent in L-shape, as at d^8 .

The crescendo-bar b^8 extends over the whole range of springs d^4 and is so arranged with reference to the springs as to form a stop coöperating with the extension d^9 of the springs to limit more or less the upward movement of the springs. Each bellows c^2 coöperates with a limited number of the springs d^4 , each bellows carrying a corresponding number of hinged spring-pressed jacks c^9 which, when the bellows is expanded, as shown in Fig. 7, stand clear of the spring d^4 , but when the bellows is collapsed, as shown in Fig. 9, the end of the jack moves over the spring d^4 in position to prevent upward movement thereof.

It will now be understood that when the springs d^4 are free to yield, a considerable portion of the force with which the key-finger d is actuated by its actuating bellows c^2 will be absorbed by the spring d^4 so that the blow delivered at the free end of the key-finger will be very light. If the yielding of any of the springs d^4 is prevented, as by the action of a bellows c^2 and its jack c^9 , the full force with which the key-finger is actuated will be transmitted through the key-finger and delivered at its free end, while in proportion as the yielding of the springs is restricted, as by the crescendo-bar b^8 , the force delivered through the key-fingers d will be decreased. The force with which the piano-string is struck by the hammer will, therefore, depend upon the extent to which the yielding of the spring d^4 is prevented, the

full tone which the corresponding power pneumatic is capable of effecting being produced whenever the corresponding spring d^4 is held from yielding, while the strength of the tone is moderated in proportion to the extent to which the spring is permitted to yield. Obviously, if all of the springs d^4 are permitted to yield except those which are selected by the performer through the movement of the handle c^6 and the collapsing of the corresponding bellows, the harmony will be subdued while the melody will be caused to predominate. The relative extent to which the harmony is subdued is under the control of the performer through the movement of the crescendo-bar b^6 , while the melody tones will respond always to the action of the bellows by which the vacuum is maintained, the expression being therefore under the control of the performer through the pedals by which such bellows are operated.

It has already been stated that the invention is applicable, in part at least, to musical instruments of various kinds, whether mechanical or automatic or otherwise, and that in mechanical or automatic musical instruments it is applicable no less to instruments which embody the mechanical or automatic playing device, commonly known as player-pianos, than to mechanical or automatic musical instruments in which the mechanical or automatic playing devices are located outside of the case of the instrument and operate through the ordinary keys of the instruments, as in any cabinet player. An embodiment of the invention in a cabinet player-piano has already been described in detail and an embodiment of the invention in a player-piano will now be described. So much of a player-piano as is necessary to enable the application of the invention to be understood is shown in Figs. 10 and 11 of the drawings. As shown particularly in Fig. 11 each piano-key, a portion of one of which is shown at e , acts through a lifter f upon a lever g which corresponds to the key-finger d of the cabinet player already described. The automatic or mechanical playing devices are sufficiently represented by the usual stem e' which is acted upon by the usual pneumatic bellows, not shown, and in turn acts, through the lifting head f , upon the key finger g which is shown as pivotally connected with the upper end of the head f . The free end of the key-finger g is shown as connected by a link h with the lever h' , which through the jack h^2 and its appurtenances acts upon the hammer h^3 . The key-finger g is movably or yieldingly fulcrumed, as at g' , and the fulcrum is preferably held or suspended yieldingly by a spring g^2 , the tension of which may be adjusted by a wire yoke g^3 shown in Figs. 11 and 12, which is secured in the frame of the mechanism and engages the spring at any desired point be-

tween the coils thereof. A guide pin g^4 is provided for the fulcrum end of the key-finger g to prevent lateral displacement thereof as the fulcrum moves or yields. For every three or four key-fingers g there is provided a bellows i which corresponds to the bellows c^2 of the cabinet player already described. It may be stated here that the number of key-fingers to each bellows or action varying or controlling device may be varied as the judgment of the manufacturer suggests, but since a tone of the melody rarely has a tone of the harmony or accompaniment within three or four half tones, it is found in practice that each action modifying device may be safely made to modify or vary the action of three or four tone producing devices, such as are represented by the key-fingers d or g which form parts thereof.

Each of the series of bellows i is suitably connected with the controlling mechanism, as through a tube c' , and the controlling mechanism may be constructed and arranged as already described with reference to the illustrated embodiment of the invention in a cabinet player. Each bellows i also carries a block or stop i' which, standing normally out of the path of movement of the fulcrum of the key-finger g so that normally such movement is not prevented or impeded, is moved by the collapsing of the bellows i into the path of movement of the several fulcra controlled by it and therefore limits or prevents the movement of such fulcra. The operation of the corresponding device in the cabinet player having already been described, it will be understood that when the block or stop i' is in its normal position the fulcrum of the key-fingers, which may be operated either by the automatic playing devices or otherwise, will yield so that the force of the blow with which the key-finger is actuated will be partly absorbed in the yielding of the fulcrum and the force transmitted at the free end of the key-finger will be correspondingly reduced. There is also provided in the embodiment of the invention now being described a crescendo-bar k , which may be moved more or less toward or from the fulcrum ends of the key-fingers g so as to limit in different degree the movement or yielding of the fulcrum, as also fully described with respect to the cabinet player. This crescendo-bar k is shown in the present embodiment as connected to a rock-shaft k' , which may be provided with an operating arm k^2 for communication through a link k^3 to a pneumatic or other actuating means. It will be unnecessary to describe again, with respect to this embodiment of the invention, the manner in which the selection of the tones to be varied or modified is placed under the control of the performer or, it might be, of automatically

controlled means, since the bellows i and the crescendo-bar k may be actuated and controlled by devices the same as those already described with respect to the cabinet player.

It has already been suggested herein that the invention is not dependent upon a particular kind of power by which the playing devices are actuated. The embodiments of the invention already described are such devices as are of the ordinary pneumatic variety in which the source of power is the vacuum maintained by the usual means. The invention is also applicable to musical instruments operated through some other source of power, and an illustration of the embodiment of the invention in an electrically actuated piano is illustrated in Figs. 13, 14 and 15, which embodiment will now be described.

The controller, through which the selection of the tones to be modified is made by the performer or otherwise, is substantially like the controller already described comprising, as indicated in Figs. 13 and 14, a terminal-board m supported at its outer end by the spring m^1 and hinged or pivoted at its rear end, as at m^2 , so as to swing upon a horizontal axis. An arm m^3 extended rearwardly from the board is connected by a link m^4 with one arm of the lever m^5 the other arm of which is connected by a link m^6 through a yoke m^7 with one arm of the bell-crank lever m^8 . The other arm of the bell-crank lever is connected with a crescendo-bar m^9 suitably supported by links and held normally in its highest position by the springs m^{11} .

On the board m near its forward edge are contacts n which form the terminals of the conductors n' which are severally connected to several electro-magnetic devices such as solenoids, one of which is shown at n^2 in Fig. 13, while a series of such solenoids is indicated in Fig. 15. Each of the solenoids, as it is magnetized or demagnetized, controls, varies or modifies the action of a small number of key-fingers. On the board m is mounted so as to move in a plane parallel therewith a shifting connector or controller through which any one of the several solenoids n^2 may be connected with the source of electrical energy, such connector or controller comprising an extensible handle n^3 , pivotally mounted in a yoke n^4 on the upper end of a vertical rock-shaft n^5 which may be connected as already described with respect to the construction shown in Fig. 1 through an arm n^{16} , link n^{17} and lever n^{18} with an indicator (not shown) in proximity to the music-sheet. The extensible handle n^3 carries a conductor n^6 which completes the circuit to the source of electrical energy, which has connected to it on the other side the several solenoids n^2 . On the under side of the head n^9 as indicated by dotted lines

in Fig. 14, is an L-shaped contact n^{19} which is connected through the conductor n^6 with the source of electrical energy. The short arm of this contact or terminal, substantially parallel with the axis of the lever n^3 , may make contact with only one of the terminals n when the head n^9 is pushed in, as is shown in Fig. 14. The long arm of the contact n^{19} makes contact with two or more of the terminals n when the head n^9 is pulled out. Therefore either one or more than one of the solenoids n^2 may be energized according to the position of the head n^9 and through the swinging of the controller to the one side, and the solenoid or solenoids which is or are to be energized may be selected from the whole series of solenoids at the will of the performer or otherwise.

A switch n^{23} is mounted on the lever n^3 as shown in Figs. 13 and 14 in a convenient position for control by the performer and is connected to the source of electrical energy, and solenoid n^{25} , as shown in Figs. 13 and 16, the core of which is connected by a rod n^{27} with a yoke m^7 through which the crescendo-bar is operated as already described, so that the crescendo-bar may be actuated either by hand through the movement of the terminal-board on its hinge or pivot or through the solenoid.

In the embodiment of the invention now being described key-fingers o , corresponding to the key-fingers d and g of the constructions shown in Figs. 7 and 11, are shown as actuated through a rod o' , from an electromagnetic device o^2 . The fulcrum of each finger is movable, and, as previously described each finger is preferably mounted on a yielding or spring-suspended fulcrum, each fulcrum-block or flange o^8 in which the key-finger is pivoted being secured to a separate flat spring o^4 . All of the springs o^4 bear upon a common fulcrum-bar o^5 , and each is provided with an adjusting spring or screw o^6 . A stop or rest-bar o^7 limits the downward movement of the free ends of the springs o^4 , which free ends may be stepped or bent in L-shape as at o^8 .

As previously described with respect to the cabinet player, the crescendo-bar m^9 extends over the whole range of springs o^4 and is so arranged as to constitute a stop co-operating with the extensions o^8 of the springs to limit more or less in different degree, the upward or yielding movement of the springs and shifting of the fulcrum-blocks. Each solenoid n^2 co-operates with a limited number of the springs o^4 , each carrying a hinged spring pressed block n^8 , which, when the solenoid is demagnetized, stands clear of the spring o^4 , but when the solenoid is magnetized the end of the block moves over the spring o^4 in a position to prevent the upward or yielding movement thereof.

The mode of operation of the invention when embodied in such a structure as that last described will be readily understood in view of the detailed description of the embodiment of the invention in a cabinet player and need not be further explained herein.

Various other modifications or embodiments of the invention will suggest themselves and changes in details of construction and arrangement may be made to suit different instruments to which the invention is applied. It will be obvious, therefore, that the invention is not restricted to the particular construction shown and described herein.

I claim as my invention.

1. In a musical instrument, the combination of a series of actuating devices, a series of tone-producing devices, mechanical transmitting devices whereby the tone-producing devices are actuated severally by the actuating devices, mechanical means acting directly upon said mechanical transmitting devices to vary the action of all of the tone-producing devices collectively, and a series of mechanical means, independent of the last named means and acting directly and severally upon said mechanical transmitting devices simultaneously with said last named means, for varying each the action of one or more of said tone-producing devices at will.

2. In a musical instrument, the combination of a series of actuating devices, a series of tone-producing devices, mechanical transmitting devices whereby the tone-producing devices are actuated severally by the actuating devices, mechanical means acting directly upon said mechanical transmitting devices to vary the action of all of the tone-producing devices collectively, a series of mechanical means, independent of the last named means and acting directly and severally upon said mechanical transmitting devices simultaneously with said last named means, for varying each the action of one or more of said tone-producing devices at will, and selective means for determining the operation of any of said series of mechanical devices.

3. In a musical instrument, the combination of a series of actuating devices, a series of tone-producing devices, mechanical transmitting devices whereby the tone-producing devices are actuated severally by the actuating devices, mechanical means acting directly upon said mechanical transmitting devices to vary the action of all of the tone-producing devices collectively, a series of mechanical means, independent of the last named means and acting directly and severally upon said mechanical transmitting devices simultaneously with said last named means, for varying each the action of one or more of said tone-producing devices at will,

actuating means for said series of mechanical means, and selective means for placing any of said series of actuating devices in operative relation with said actuating means.

4. In a musical instrument, the combination of a series of actuating devices, a series of tone-producing devices, mechanical transmitting devices whereby the tone-producing devices are actuated severally by the actuating devices, mechanical means acting upon said mechanical transmitting devices to vary the action of all of the tone-producing devices collectively, a series of mechanical means, independent of the last named means and acting severally upon said mechanical transmitting devices simultaneously with said last named means, for varying each the action of one or more of said tone-producing devices at will, a source of power, and a controller and selective connections through which any of said series of mechanical means can be placed, in operative relation with said source of power.

5. In a musical instrument, the combination of a series of player pneumatics, a series of tone-producing devices, mechanical transmitting devices whereby the tone-producing devices are actuated severally by the actuating devices, mechanical means acting upon said mechanical transmitting devices for varying the action of all of the tone-producing devices collectively, a series of independent mechanical devices acting severally upon said mechanical transmitting devices for varying each the action of one or more of the tone-producing devices, a corresponding series of terminals to which said devices are operatively connected severally, a shiftable controller comprising a terminal for coöperation with any of said series of terminals, and a common source of power connected to the terminal on the controller.

6. In a musical instrument, the combination of a series of player pneumatics, a series of tone producing devices, mechanical transmitting devices whereby the tone-producing devices are actuated severally by the actuating devices, a series of independent mechanical devices acting upon said mechanical transmitting devices severally for varying each the action of one or more of the tone-producing devices, a corresponding series of terminals to which said devices are operatively connected severally, a shiftable controller comprising a terminal for coöperation with any of said series of terminals and a common source of power connected to the terminal on the controller.

7. In a musical instrument, the combination of a series of actuating devices, a series of key-fingers, mechanical connections whereby the key-fingers are actuated severally by the actuating devices, a series of yielding supports for said key-fingers, a series of de-

5 vices coöperating with said supports to limit the movement thereof, and selective means for actuating any of said devices.

6 8. In a musical instrument, the combination 5 of a series of actuating devices, a series of key-fingers, mechanical connections whereby the key-fingers are actuated severally by the actuating devices, a series of devices acting upon said connections, a series of yielding supports for said key-fingers, a series of devices coöperating with said supports to limit the movement thereof, actuating means for said series of devices, and selective means for placing any of said devices in operative relation with said actuating means.

10 9. In a musical instrument, the combination 10 of a series of actuating devices, a series of key-fingers, mechanical connections whereby the key-fingers are actuated severally by the actuating devices, a series of devices acting upon said connections, a series of yielding supports for said key-fingers, a series of devices coöperating with said supports to limit the movement thereof, a common source 25 of power, and a selective controller and connections through which any of said devices can be placed in operative relation with said source of power.

15 10. In a musical instrument, the combination 30 of a series of actuating devices, a series of key-fingers, mechanical connections whereby the key-fingers are actuated severally by the actuating devices, a series of devices acting upon said connections for varying each the action of one or more of the key-fingers, a series of terminals to which said devices are operatively connected severally, a shiftable terminal for coöperation with any of said series of terminals, and a 35 source of power connected to said shiftable terminal.

15 11. In a musical instrument, the combination 45 of a series of actuating devices, a series of key-fingers, mechanical connections whereby the key-fingers are actuated severally by the actuating devices, a series of devices acting upon said connections for varying each the action of one or more of the key-fingers, a series of bellows operatively 50 connected with said devices severally, a corresponding series of terminal ports and connections to said bellows severally, and a shiftable terminal connected with the vacuum system and adapted to establish connection between any of said bellows and the 55 vacuum system.

15 12. In a musical instrument, the combination 60 of tone-producing devices, a series of bellows and mechanical devices for varying each the action of one or more of said tone-producing devices at the will of the performer, a corresponding series of terminal ports and connections to said bellows severally, a shiftable controller, a terminal con-

6 nected with the vacuum system and shiftable with said controller and adapted to establish connection between any of said bellows and the vacuum system, a valve for controlling the connection between said terminal and the vacuum system, and a terminal 70 carried by the controller and operatively connected with said valve, whereby the connection between all of said bellows and the vacuum system may be controlled by the performer.

75 13. In a musical instrument, the combination 75 of tone-producing devices, a series of devices for varying each the action of one or more of the tone-producing devices at the will of the performer, a corresponding series of terminals and connections to said series of devices, a shiftable controller, a source of power, a terminal shiftable with the controller and connected with the source of power and adapted to establish connections between any of said series of terminals and the source of power, and means under the control of the performer for controlling the connection between the shiftable terminal and the source of power.

80 14. In a musical instrument, the combination 80 of tone-producing devices, a series of devices for varying each the action of one or more of the tone-producing devices, a series of terminals connected with said series of devices severally, a shiftable controller, a source of power, a terminal shiftable with the controller and connected with the source of power and adapted to establish connection from the source of power to any of said 85 series of devices through the respective terminals of the series, a crescendo-bar to coöperate with all of the tone-producing devices, and an operative connection between the controller and the crescendo-bar, whereby the crescendo-bar may be actuated by the movement of the controller.

90 15. In a musical instrument, the combination 90 of tone-producing devices, a series of bellows and devices controlled thereby for varying each the action of one or more of the tone-producing devices, a vacuum system, a pivoted terminal board, a series of terminal ports carried by the terminal board and connected with said bellows severally, a controller mounted on said board, a terminal carried by the controller and establishing connection between the vacuum system and any of said bellows through said series of terminal ports, a crescendo-bar to coöperate 100 with all of the tone-producing devices, and a connection between the pivoted terminal board and the crescendo-bar.

105 16. In a musical instrument, the combination 105 of tone-producing devices, a series of actuating devices and mechanical transmission devices, a series of devices acting upon said mechanical transmission devices for

varying each the action of one or more of the tone-producing devices, a corresponding series of terminals to which said devices are operatively connected severally, a shiftable controller, a shiftable terminal for coöperation with any of said series of terminals, a source of power connected to the shiftable terminal, a crescendo-bar to coöperate with all of the mechanical connections between the actuating devices and the tone-producing devices, means to actuate the crescendo-bar from the source of power, and means under the control of the performer for controlling the connection of said actuating means with the source of power.

17. In a musical instrument, the combination of tone-producing devices, a series of actuating devices and mechanical transmission devices, a series of bellows acting upon said mechanical transmission devices for varying each the action of one or more of the tone-producing devices, a corresponding series of terminal ports with which said bellows are operatively connected severally, a shiftable controller, a shiftable terminal adapted to establish connection between the vacuum system and any of said bellows through said series of terminals, a crescendo-bar to coöperate with all of the mechanical connections between the actuating devices and the tone-producing devices, a bellows and connection to actuate the crescendo-bar, and a terminal under control of the performer and connections to determine the operation of the last named bellows.

18. In a musical instrument, the combination of a series of actuating devices, a series of tone producing devices, mechanical transmission devices, a series of mechanical devices acting upon said mechanical transmission devices for varying each the action of one or more of the tone-producing devices, a selective controller and connections for determining the operation of one or another of said series of devices, and an indicator in proximity to the music-sheet and operatively connected with the controller to move therewith.

19. In a musical instrument, the combination of a series of actuating devices, a series of tone-producing devices, mechanical transmission devices, a series of mechanical devices acting upon said mechanical transmission devices for varying each the action of one or more of the tone-producing devices, a corresponding series of terminals operatively connected with said series of devices severally, a source of power, a shiftable controller, a shiftable terminal adapted to establish connection between any of said series of devices through the series of terminals and the source of power, and an indicator in proximity to the music-sheet and operatively connected with the controller to move therewith.

65

troller, a shiftable terminal adapted to establish connection between any of said series of devices through the series of terminals and the source of power, and an indicator in proximity to the music-sheet and operatively connected with the controller to move therewith.

20. In a musical instrument, a tone-producing mechanism including a lever with a movable fulcrum adapted to yield bodily during the playing movement and means for limiting the movement of the fulcrum.

70

21. In a musical instrument, the combination of a tone-producing mechanism including a lever having a yielding fulcrum adapted to yield bodily during the playing movement and means for limiting the yielding of the fulcrum.

75

22. In a musical instrument, the combination of a tone-producing mechanism, including a lever and a spring-suspended fulcrum block therefor adapted to yield bodily during the playing movement, and means for limiting the yielding of the fulcrum block.

80

23. In a musical instrument, the combination of a series of playing devices having each a lever with a movable fulcrum adapted to yield bodily during the playing movement and means for limiting the movement of the fulcrum.

85

24. In a musical instrument, the combination of a series of playing devices having each a lever with a yielding spring suspended fulcrum, and means for limiting the movement of the fulcrum.

90

25. In a musical instrument, the combination of a series of playing devices having each a lever with a yielding fulcrum and means for limiting in different degrees the yielding of the fulcrum of all the levers.

95

26. In a musical instrument, the combination of a series of playing devices having each a lever with a yielding fulcrum and means for limiting the yielding of any of the fulcrum.

100

27. In a musical instrument, the combination of a series of playing devices having each a lever with a yielding fulcrum, means for limiting in different degrees the yielding of the fulcrum of all the levers and independent means for limiting the yielding of any of the fulcrum.

105

This specification signed and witnessed this 5th day of July, A. D., 1909.

HENRY S. HORNBECK.
